Application May 23, 1941, Serial No. 394,805

16 Claims. (Cl. 263—9)

This invention relates to a portable rail end heater. More particularly, it relates to a pre-heater for use in heating abutting ends of rails at a joint in track.

Several existing processes for treating rail ends lying in track require equipment for heating a rail end preparatory to the performance of other steps. Thus, one rail end hardening process requires a pre-heater for raising the temperature of the rail ends so that a quenching step may be performed. Again some processes for building up battered rail ends require a pre-heating of the rail ends preparatory to laying a bead of weld metal thereon, and one such process calls for the maintenance of the tips of the abutting rail ends at a temperature lower than the temperature at a point on the rail ball spaced some distance back from the tip.

With the foregoing desiderata in mind, one object of this invention is to provide a portable pre-heater having two heating units for pre-heating two abutting rail ends in a rail joint lying in track. By the employment of two heating units, it is possible to avoid applying heat to the tips of the rail ends by positioning the heating units on opposite sides of the joint. By mounting the two heating units on a single frame, the pre-heater remains a unit and its movement from rail joint to rail joint is simplified.

Another object of this invention is to provide means for quickly varying the distance between the two heating units in order to perform more efficiently the pre-heating step of a well known rail end rebuilding process. That part of the last named process pertinent to this invention comprises marking the two points on the abutting rail ends at which the rebuilding is to begin and then centering a pre-heater over each of these two points so that the highest temperature will be held at these points for the longest time during cooling—all preparatory to performing certain other steps in the process. It will be appreciated that the distance from the rail end to a point at which a weld is to begin will vary. In fact it is not uncommon that a weld bead in one rail end of a joint will be four or five inches long while the weld bead in the abutting rail end will be seven or eight inches long. The above mentioned object of this invention, therefore, seeks to provide means in connection with a portable heater, that is, one which is a unit that may be moved manually from joint to joint, for varying the distance between two heating units quickly in order that the portable heater may be set on the balls of the two rail ends at a joint with the

center of one heating unit on the point where the weld is to begin in one rail end and the center of the other heating unit over the point in the other rail end where the weld is to begin.

5 Another object of this invention is to provide means for automatically centering a portable pre-heater on the rails. The centering here referred to is lateral centering of the heating units on the ball of the rail. As will more clearly appear hereinafter, the pre-heater which is the subject of this invention has two heating units, each of which have two substantially aligned flame directing inverted channels open at each end for permitting the heating units to drop down over the sides of the ball of the rail so as to cause the downwardly directed flame to curl downwardly along both sides of the rail ball. These flame directing inverted channels are broader than the width of the rail ball in order to permit the flame and hot gases to move downwardly around the rail ball and in order to accommodate different sized rails. Into these flame directing inverted channels open a plurality of aligned flame tunnels which for most efficient operation should be centered over the ball of the rail. In order to accomplish this, the applicant provides centering plates, one on each heating unit, which upon the positioning of the portable pre-heater on the joint, automatically center laterally the heating units on the balls of the two rail ends.

20 A further object of this invention is to provide a novel handle and foot supporting arrangement which results in a certain safety factor when carrying the portable pre-heater from rail joint to rail joint while the heating units are very hot. One of the features of this invention is the suspension of the entire pre-heater pivotally from a handle, which is above and at one side of the center of gravity of the heater. By this arrangement, when the pre-heater is lifted by the handle by one standing on that side of the pre-heater away from the handle, the pre-heater will swing away from the lifter. The heating units do likewise.

25 35 40 45 A further object of this invention is to position the heating units above the rail ball so as to obtain a maximum heating effect in the ball of the rail. One of the conditions which this burner is required to meet is the limited capacity of the inspirators to add gas to form a combustible mixture. While it would be possible to provide a pressure pump for increasing the amount of air which could be added to the gas, such equipment when used on track is cumbersome and increases the cost of operation. In short, such equipment

impairs the general portability of the pre-heater. Toward attaining this object, the applicant positions the flame tunnels sufficiently far above the rail so that in conjunction with the depending sides of the inverted channel, into which the flame tunnels open, the total cross-sectional area on both sides of a rail when the heating units are resting on the rail will be approximately equal to the cross-sectional area of the three flame tunnels. Experiments have demonstrated that increasing or reducing the cross-sectional area of the gas escape on both sides of the ball of a rail will impair the rapidity of the heating of the rail balls.

Another object of this invention is to provide a heater heating unit of long life. The heating units in applicant's type of heater must be able to withstand high temperatures. Thus, in practicing the process of building up battered rail ends, it is necessary that each heating unit be capable of raising the temperature of the ball of the rail to 700° F. within approximately two minutes. The use of ordinary refractory material at points in the heating unit exposed to the flame, particularly in the flame tunnels, has not been found satisfactory. Frequent changes in temperature due to reducing the flame in the heating units when moving the heater from joint to joint, together with the out of doors conditions under which this work is performed, results in rapid disintegration of the refractory material in the heating unit. One of the features of this invention is the employment of Nichrome liners in the heating unit flame tunnels beneath the burner screens. Nichrome is a nickel, chromium, iron alloy which is highly resistant to heat. These liners are positioned between the refractory burner screens and that portion of the heating unit immediately above the rail ball so as to protect the non-metallic refractory material used at other points in the heating unit.

The invention includes certain other improvements as, for example, the mounting of a time clock and a bell, and a comparatively inexpensive method of securely positioning the Nichrome tunnel liners to surrounding refractory material. These and such other objects as may hereinafter appear are attained in one embodiment of this invention shown in the accompanying drawings, wherein:

Figure 1 is a perspective view of the pre-heater illustrating its safety feature when being carried;

Figure 2 is a side view in elevation of the pre-heater, with the left-hand unit shown in section, the same being positioned at a rail joint with one heating unit closer to the rail joint than the other heating unit;

Figure 3 is an end view of the pre-heater;

Figure 4 is an end view partly in section of a heating unit taken on the line 4—4 of Figure 2;

Figure 5 is a side view partly in section of a heating unit;

Figure 6 is a view taken on the line 6—6 of Figure 5; and

Figure 7 is a view of a tube which functions jointly as a main frame support for the pre-heater and as a manifold.

Continuing to refer to the drawings and particularly to Figure 1, the principal elements of applicant's pre-heater comprise two heating units 10 and 12 supported respectively by two brackets 14 and 16 which in turn are maintained in aligned relationship by being fastened to a heavy tubular member 18, which as will hereinafter appear functions as a manifold positioned in the

gas supply line. The two heating units 10 and 12 have downwardly directed open ended inverted channels 20 and 22, together with tunnels therein for directing flame downwardly into the inverted channels 20 and 22, all of which will be more particularly described hereinafter. The two heating units 10 and 12 are supplied with gas through two inspirator bodies 24 and 26 from gas jet assemblies 28 and 30. These two gas jet assemblies 28 and 30 are supplied with gas from the supporting tube or manifold 18, which receives gas from any suitable source through a conduit 32.

By the arrangement of parts shown in Figure 1 and described in the preceding paragraph, applicant has provided a portable rail end heater having two heating units which may be positioned at a rail joint, astride the joint. That portion of the ball of the rail beneath the center 20 of each heating unit will become the hottest point on the ball of the rail when the heating unit is operating normally and hence, referring to Figure 2, it will be understood that the tips of the rail ends which are not beneath either of the heating units will become heated primarily by conduction and that in consequence these tips will be at a lower heat than portions of the rail spaced from the tips and immediately beneath the heating units. By this arrangement, it is possible to heat two rail ends quickly with the point of highest temperature in each rail end at a short distance from the tip of the rail end, all as required in certain processes of rail end rebuilding.

Further describing the invention and again referring to Figure 1, each of the brackets 14 and 16 are attached at their upper portions to sleeves 34 and 36 having an inside diameter sufficiently great to permit these sleeves 34 and 36 to be slipped longitudinally of the supporting tube 18. The heating unit 10 and the bracket 14 are maintained in fixed relationship to the supporting tube 18 by means of the set screw 38 threadedly engaging the wall of the sleeve 34 and pressed against the supporting tube 18. The heating unit 12 and the supporting bracket 16 may be moved longitudinally of the supporting tube 18 by sliding the sleeve 36 along the supporting tube 18 and utilizing a wing set screw 40 for holding the heating unit at any desired distance from the heating unit 10. Attention is invited to the means for maintaining the brackets such as 14 and 16 in assembled relationship to the sleeves 34 and 36. Referring to Figure 3, it will be noted that a plate 15 rigidly fastened to the bracket 16 is held to a depending plate 17 rigidly fastened to the sleeve 36 by means of a bolt 43 and a nut 44. A hole 45 in the plate 15 has a greater diameter than the diameter of the shank of the bolt 43 and the nut 44 is not drawn up tightly so that the bracket 16 is only loosely held to the sleeve 36. The purpose of this loose mounting is to make it possible for each heating unit to adjust itself to the surface of the particular rail upon which it is resting. Rail ends at a joint are not necessarily in alignment and the canting of the two rails may be slightly different. In order that each heating unit may seat itself firmly on each rail end, it is desirable to provide a little play between each heating unit and the supporting framework.

It will be noted, referring to Figure 2, that the supporting tube or manifold 18 is not centered with respect to the pre-heater as a whole, the reason for this being that longitudinal movement

of only one of the heating units is necessary to accomplish the purpose desired and it is consequently possible to move the manifold to that side of the pre-heater which will carry the longitudinally movable heating unit while positioning a gas pressure gauge 47 and a time clock 49 together with gas connections to the manifold at the other end of the pre-heater. It will also be understood that the gas connection 46 from the manifold to the gas jet assembly 28 is flexible in order to permit movement of the heating unit 12 longitudinally of the manifold or supporting tube 18. The gas line 48 connecting the manifold 18 to the gas jet assembly 30, on the other hand, need not be flexible and may be a metal tube.

It is thus seen that the distance between the two heating units may be varied by simply loosening the wing set screw 40. By this arrangement it is possible to establish the hottest spot in the ball of the rail at the point where the weld ends, regardless of the fact that the end of the weld on one of the two abutting rail ends may be five inches from the rail joint while the end of the weld on the other rail end is seven or eight inches from the rail joint. Thus, in Figure 2, there is illustrated a rail 50 having a battered end commencing at the point 52, which is perhaps five inches from the rail joint 54. The abutting rail 56 has a battered end commencing at the point 58 some eight inches from the end of the rail. According to certain rail end rebuilding processes now practiced, the pre-heating step should produce the highest heat at the points 52 and 58 while permitting the tips of the rail to remain comparatively cool. It is evident, referring to Figure 2, that by positioning the heating unit 10 so that its center is over the point 52, the heating unit 12 may be moved away from heating unit 10 until its center is above the point 58. If a rail end is battered commencing at a point less than five inches from the tip, it would be necessary for the heating unit to overlap the rail joint if the heating unit center (the heating units being about ten inches long) is to be placed immediately over the point where the weld is to begin. It is not, however, the practice to permit either heating unit to overlap the joint 54. In such a case, the hottest point on the ball of the rail will not be immediately over the point where the weld is to commence but a slight distance 50 farther away from the tip of the rail.

A further feature of this invention is the positioning of the handle to one side of the center of gravity of the pre-heater whereby lifting the pre-heater by the handle from the side away from the handle will cause the hot heating units to assume such a position that the heater elements will be directed away from one carrying the heater. Referring to Figure 1, disposed on the supporting tube 18 between sleeves 34 and 36 is a third sleeve 60 to which is attached by any suitable means an arm 62 carrying a handle 64, which handle is substantially parallel to the supporting tube 18. Also attached to the sleeve 60 is a leg 66 in the base of which is an adjustable pin 68. Referring now to Figure 3, the relationship of the handle 64 and the leg 66, on the one hand, to the supporting tube 18 and the center of gravity of the pre-heater as a whole may be seen. The center of gravity is to the right of a vertical line passed through the supporting tube 18, and in consequence of this, when the pre-heater is lifted by the handle 64, the supporting tube 18 together with the brackets 14 and 16, the inspirator bodies 24 and 26 and the heating units 10

and 12 rotate clockwise until the center of gravity is beneath the supporting tube 18 and the handle 64. By lifting the pre-heater from the right-hand side as shown in Figure 3 or in the manner actually shown in Figure 1, the pre-heater including two heating units 10 and 12 are tilted away from the body of the person carrying the pre-heater.

Returning to Figure 3, the leg 66 is bent so as to assist in holding the pre-heater in an erect position when the heating units are resting upon a rail joint. An adjustable pin 68, having a sharp tip, engages the ballast or a tie. The leg 66 may be tubular throughout or hollowed at its end so that the adjustable pin 68 may be slid therein and held at any desired point by a set screw 70, see Figure 1.

Another feature of this invention resides in the heating units. Referring to Figure 5, each heating unit comprises a housing 72, the upper portion of which contains a chamber 74 having as a bottom a crown sheet 76 fastened to the walls of the housing by any suitable means. The crown sheet 76 contains three holes 78, 80 and 82 positioned in alignment lengthwise of the heating unit, see Figure 6. In each of these holes is positioned a refractory burner screen, as 84, 85 and 88, see Figure 6. These burner screens carry shoulders which engage the crown sheet and are held tightly thereagainst by two flange members 90 and 92, see Figure 4, which in turn are held in position by wing nuts such as 94 and 96 drawn tightly upon bolts such as 98 and 100 which are fastened to the crown sheet 76, as shown in Figure 5, by any suitable means. The housing 72 has two end walls 102 and 104, which ends are cut upwardly from their bottoms to form the channel 20. Flanges 106 and 108, see Figures 4 and 5, are attached to the end walls by any suitable means and follow the curvature of the cut-out, forming the channels 20 and 22.

Beneath each of the three refractory burner screens is positioned a Nichrome tunnel liner as 110, 112 and 114. The space beneath the crown sheet 76, excepting for the channel 20 and the interior of the tunnel liners 110, 112 and 114, is filled with a refractory material which is positioned while still in the plastic or cementitious state. The refractory material upon hardening holds the Nichrome tunnel liners 110, 112 and 114 in the position shown beneath the refractory burner screens 84, 85 and 88 respectively.

The employment of a Nichrome liner for a burner tunnel solved a serious wear problem which was encountered so long as non-metallic refractory material only was used for the flame tunnel walls. The refractory material deteriorated rapidly due to the high heat and hard usage. As soon as the walls broke down the flame was no longer directed properly against the ball of the rail. The Nichrome tunnel liners, being capable of withstanding intense heat without disintegration or deformation, completely solved this problem.

Holding the Nichrome liners in the refractory material is effected by providing a collar such as 116 for each Nichrome liner and packing the refractory material while in the plastic state around the liner so as to engage the collar 116 and hold the liner in place. The actual method of building the heating unit after the crown sheet 76 has been properly mounted in the housing 72 is to position jig plugs having an outside contour like each burner screen plus an extension to fit the inside of a Nichrome liner in the

holes 78, 80 and 82 and to hold the jig plugs tightly by means of the flanges 90 and 92 and wing nuts 94 and 96. The heating unit is then inverted and the three Nichrome tunnel liners are slipped down over the three jig plugs. The refractory material, in cement form, is then packed into the spaces between the outside walls of the Nichrome tunnel liners and the inside of the housing 72. The jig plugs are next removed and replaced by the burner screens.

The construction of the Nichrome tunnel liners consist merely in wrapping a Nichrome wire 116 around the outside upper edge of the liners and then making a plurality of welds to establish a firm relationship between the wire and the liner. This method is far less expensive than rolling a shoulder or casting the Nichrome liner with a shoulder.

The means for assembling the heating unit in the pre-heater consists of four bolts such as 118 and 120, see Figure 5, positioned around a large opening 122 centrally of the top of the heating unit housing 72. The opening 122, see Figure 4, is sufficiently large to permit access to the chamber 74 so that the flanges 90 and 92 and any one of the burner screens 84, 86 and 88 may be removed for repair or replacement. The bolts 118 and 120 seat in holes in the brackets such as 16 in Figure 4 with a shoulder 124, see Figure 2, on an elbow 126 connected by a nipple 128 to the inspirator body 24 positioned between the top of the housing 72 and flanges on the bracket 16.

Another feature of this invention is the employment of centering plates. Referring to Figure 2, two centering plates 130 and 132 on the heating units 12 and 10 respectively are held for vertical reciprocable movement by means of two flanges, which may best be seen in Figure 1 and which bear the numbers 134 and 136. Each of the centering plates, such as 130, has a cut-out portion 138 in its bottom which is gently tapered to a top horizontal portion of a width slightly less than the width of the ball of the rail. Each centering plate, referring to Figure 2, is urged downwardly by a spring member 140 which is held by the bolts holding the heating unit 12 to its associated bracket. The centering plate 130 cannot drop below a desired height because of an inwardly turned edge 142 which engages the top of the heating unit. It is evident that the configuration of the opening 138 in the bottom of each of the centering plates will, when the pre-heater is rested upon the balls of the two rail ends in a joint, tend to center the heating unit over the rail, and, inasmuch as the two centering plates are mounted at the opposite ends of the two heating units, will have the effect of properly aligning the entire pre-heater with respect to the joint.

Attention is now invited to Figure 4 for the purpose of pointing out the relationship of the openings 111 and 113 to the tunnels. Referring to Figure 5, it will be noted that each of these openings 111 and 113 are rectangular in cross-section and are defined by the inside walls of the heating unit and the ball of the rail, the actual cross-sectional area being determined by the relationship, returning to Figure 4, of the flanges such as 106 to the bottoms of the tunnel and the refractory material. The size of the openings 111 and 113 is not fortuitous. Extended experiments wherein the bottom openings of the tunnels were positioned closer to the ball of the rail or farther from the ball of the rail than the distance shown in Figure 4 were conducted and

in each experiment the temperature rise in the rail ball after a common heating period was checked. It was found that the distance shown in Figures 4 and 5 resulted in the highest heat in the rail when the particular gas supply system employed was used. The cross-sectional area of the openings 111 and 113 together are approximately equal to the cross-sectional areas of the three tunnels and it was concluded that this relationship provided the best results regardless of changes in the pressure of the gas through the inspirators. When the bottoms of the tunnels (and the heating unit as a whole) were raised farther above the rail, it was believed that the burning gases did not properly impinge upon the surface of the rail but probably swept around the sides of the rail because of the enlarged escape opening. When the tunnels were placed closer to the top of the ball of the rail, only to produce less heat, it is believed that the rapidity of combustion is impaired due perhaps to an excess back pressure on the gas line. At all events, where the burning gas escape opening is approximately equal to the cross-sectional area of the flame tunnels, highly desirable results are obtained.

It will be understood that the cross-sectional areas 111 and 113 are not always the same because while the heating units are the same, the size of rails varies. The statements in the foregoing paragraph as to the height of the tunnel bottoms above the rail ball, therefore, represent a desirable means, taking into consideration the various weights of rail that are commonly used by railroads.

Another feature contributing to the success of applicant's heating units lies in the refractory walls identified by the numerals 117 and 119. These refractory walls become hot and it has been found that they contribute considerable to the rapid heating of a rail ball by radiating heat to the rail ball.

Attention is called to the length of the handle 64, see Figures 1 and 2. It is, of course, desirable to grasp the handle at the longitudinal center of gravity of the heater. This center of gravity shifts due to moving the heating unit 12 and it is therefore, desirable to have a handle sufficiently long to permit one carrying the pre-heater to grasp the handle immediately above the longitudinal center of gravity.

In Figure 7, the construction of the manifold is shown. The manifold comprises an inner tube 146 concentrically positioned within a heavy outer tube 148, the positioning being obtained by any suitable means. A plurality of small holes establishes communication between the inside of the tube 146 and the annular space between the tube 146 and the tube 148. The manifold is tapped at 150 and the gas is introduced into this annular space. The gas reaches the inner tube 146 by the holes therein and thence flows out both ends of the inner tube to the gas jet assemblies 28 and 30.

In the particular embodiment of this invention disclosed, the equipment is designed to burn liquid petroleum gas. It will be appreciated that the equipment in the gas line including valves, burner jets, and inspirators may require modification in order to adapt the invention to some other type of fuel, such as gasoline or the like. It will further be understood that the actual embodiment shown in the drawings described herein is capable of modifications and variations

which nevertheless fall within the spirit of the invention itself.

Having thus described my invention, what I claim as new and desire to secure by Letters Patent of the United States is:

1. A portable rail joint heater comprising a frame, a pair of spaced substantially aligned heating units mounted on said frame, means on the lower part of each heating unit for positioning the heating unit on a rail ball, means laterally adjustable connecting each heating unit to the frame whereby each heating unit may properly engage a rail at a rail joint regardless of different canting between the two rails, means for supplying a combustible mixture to said heating units, and means for varying the distance between said heating units whereby the two heating units may be centered over two selected points in the two rail ends forming a rail joint irrespective of the distance of the two points from the tips of the rail ends.

2. A portable rail joint heater comprising a frame, a pair of spaced heating units mounted on said frame, an open ended inverted channel in the bottom of each heating unit of a size suitable for enclosing the ball of a rail when the heating unit is rested thereon, the inverted channels in the two heating units being in substantial lengthwise alignment, and means for supplying a combustible mixture to the heating units.

3. A portable rail joint heater comprising an elongated tubular supporting member, a heating unit suspended from said elongated tubular member at a predetermined fixed position, a sleeve around said tubular member capable of longitudinal movements thereof, a second heating unit suspended from said sleeve, whereby it is possible to move the second heating unit with respect to the first heating unit by sliding the sleeve along the tubular supporting member, and means for supplying a combustible mixture to said heating units.

4. A portable rail joint heater comprising an elongated tubular supporting member, a heating unit suspended from said elongated tubular member at a predetermined fixed position, means for supplying a combustible mixture to said heating unit from a fixed point on the tubular supporting member, a sleeve around said tubular member capable of longitudinal movements thereof, a second heating unit suspended from said sleeve, whereby it is possible to move the second heating unit with respect to the first heating unit by sliding the sleeve along the tubular supporting member, and flexible gas supply means between the second heating unit and a point on the tubular supporting member for supplying a combustible mixture to the second heating unit, whereby the second heating unit may be moved with respect to the rail joint heater as a whole.

5. A portable rail joint heater comprising a frame, a pair of heating units suspended from said frame in substantial alignment, means for supplying a combustible mixture to said heating units, means for moving the heating units relatively to each other in alignment, and an open ended inverted channel disposed in the lower part of each heating unit having a major axis substantially parallel with the line of movement of the two heating units when moved with respect to each other, said inverted channels being of a size such that the heating units may be positioned over the ball of a rail for performing a heating operation thereon.

6. A portable rail joint heater comprising a frame, a pair of heating units suspended from said frame in substantial alignment, means for supplying a combustible mixture to said heating units, means for moving the heating units relatively to each other in alignment, an open ended inverted channel disposed in the lower part of each heating unit having a major axis substantially parallel with the line of movement of the two heating units when moved with respect to each other, each of said inverted channels being of a size such that the heating units may be positioned over the ball of a rail for performing a heating operation thereon, and a centering plate on each of the heating units for engaging the ball of the rail and centering the inverted channels of each heating unit with respect thereto.

7. A portable rail joint heater comprising a frame, a pair of heating units suspended from said frame in substantial alignment, means for supplying a combustible mixture to said heating units, means for moving the heating units relatively to each other in alignment, an open ended inverted channel disposed in the lower part of each heating unit having a major axis substantially parallel with the line of movement of the two heating units when moved with respect to each other, said inverted channels being of a size such that the heating units may be positioned over the ball of a rail for performing a heating operation thereon, and mounted on each outer end of the heating units a centering plate having a tapered opening adapted to be slipped over the ball of the rail, said centering plate being capable of vertical movement only with respect to the heating units, whereby the centering plate by its tapered opening will shift the heating units laterally so as to center the inverted channel of each heating unit over the ball of each rail.

8. A portable rail joint heater comprising a tubular supporting member, a pair of heating units suspended from said tubular supporting member, means for moving the heating units relatively to each other, means for supplying a combustible mixture to said heating units, and handle carrying means disposed on said tubular supporting member at one side of the center of gravity of the rail joint heater, from that side of the center of gravity of the rail joint heater opposite to the handle, whereby lifting the heater by the handle will cause the heating units to swing away from a person so holding the heater.

9. A portable rail joint heater comprising a tubular supporting member, a heating unit suspended from one end of the supporting member at a fixed position, a sleeve capable of movement on said tubular supporting member having a second heating unit depending therefrom, means for moving the heating units relatively to each other, means for supplying a combustible mixture to the heating units, a second sleeve freely rotatable on said supporting tube, a handle affixed to the second sleeve, and a leg affixed to the second sleeve and depending to a point substantially below the heating units for engaging ballast in track whereby the rail joint heater may be supported in an upright position on the rail, the handle and the leg being disposed on the same side of the center of gravity of the rail joint heater whereby lifting the handle of the rail joint heater on that side of the center of gravity opposite to the handle and the leg will

permit the tubular supporting member to pivot in the sleeve holding the handle, thereby assisting in disengaging the leg from supporting position and during carrying swinging the heating units away from one carrying the heater.

10. A portable rail joint heater comprising a frame, a pair of heating units suspended from said frame in substantial alignment, means for moving the heating units relatively to each other, means for supplying a combustible mixture to said heating units, substantially aligned open ended inverted channels, one in the bottom of each of the heating units, means in the heating units for directing a flame toward said inverted channels, a burner screen in said heating units, tunnels between the burner screen and the associated channels of each heating unit, and a nickel, chromium, iron alloy liner in said tunnels.

11. A portable rail joint heater comprising a frame, a pair of heating units suspended from said frame in substantial alignment, means for moving the heating units relatively to each other, means for supplying a combustible mixture to said heating units, substantially aligned inverted channels, one in the bottom of each of the heating units, a crown plate forming a gas chamber in the upper part of each heating unit, a hole in said crown plate, a burner screen positioned therein, refractory walled tunnels between each burner screen and its associated channels, and nickel, chromium, iron alloy liners protecting the refractory material and disposed between the burner screen and said inverted channels.

12. A portable rail joint heater comprising a frame, a pair of heating units suspended from said frame in substantial alignment, means for moving the heating units relatively to each other, means for supplying a combustible mixture to said heating units, substantially aligned open ended inverted channels in the bottom of each of the heating units, a crown plate forming a gas compartment in the upper part of each of said heating units, a series of aligned holes in the crown plate parallel to the length of the inverted channel in the same heating unit, a burner screen in each aligned hole, a nickel, chromium, iron alloy liner disposed beneath each burner screen, and refractory material packed between said liners, inside walls of the heating unit and the crown plate.

13. A portable rail joint heater comprising a frame, a pair of heating units suspended from said frame in substantial alignment, means for

moving the heating units relatively to each other, means for supplying a combustible mixture to said heating units, substantially aligned open ended inverted channels in the bottom of each 5 of the heating units, a plurality of tunnels downwardly directed and opening into said substantially aligned open ended inverted channels, and means for supporting each substantially aligned open ended inverted channel above the rail so 10 as to create gas escape openings between the ball of the rail and the walls of the inverted channel which will be approximately equal at their smallest point in cross-section to the cross-sectional area of all of the tunnels in each heating unit.

14. A portable rail joint heater comprising a frame, a pair of heating units having means thereon for resting on the ball of a rail, means for moving said heating units relative to each 20 other, and means for enabling the heating units to move laterally with respect to their first recited movement whereby when the two heating elements are rested astride a rail joint wherein the rails are canted at different angles, each heating 25 unit may adjust itself to the rail upon which it rests.

15. A portable rail joint heater comprising a frame, a pair of heating units having means thereon for resting on the ball of a rail, means for moving said heating units relative to each 30 other and means for shifting each heating unit with respect to the frame whereby when the two heating units are rested astride a rail joint wherein the rail ends slope downwardly toward 35 the joint due to batter, each heating unit may rest squarely on the rail ball so as to be substantially parallel thereto.

16. A portable rail joint heater comprising a frame, a pair of spaced heating units suspended 40 substantially in alignment from said frame in such a manner that each may be rocked in the direction of a plane passed through both heating units, an open ended inverted channel in the bottom of each heating unit of a size suitable 45 for enclosing the ball of a rail when the heating unit is rested thereon, and means for supplying a combustible mixture to the heating units, whereby the channel of each heating unit may rest firmly on the ball of the rail end despite 50 rail end batter and without resistance from the frame.

ROYAL E. FRICKEY.
